[57] CLAIM

The ornamental design for a single phase recloser apparatus, as shown and described.

DESCRIPTION

FIG. 1 is a front and upper right perspective view of a single phase recloser apparatus showing my new design; FIG. 2 is a left side elevational view thereof; FIG. 3 is a right side elevational view thereof; FIG. 4 is a top plan view thereof; FIG. 5 is a bottom plan thereof; FIG. 6 is a front elevational view thereof; FIG. 7 is a rear elevational view thereof; and, FIG. 8 is a front and lower right perspective view of my new design.

The broken line showings throughout the drawing figures are included for the purpose of illustrating environmental elements only and forms no part of the claimed design.
